UNITED STATES PATENT OFFICE.

WILLIAM E. HOLDER AND RICHARD SAMPSON, OF MONTREAL, QUEBEC, CANADA; SAID HOLDER ASSIGNOR TO SAID SAMPSON.

HOT PLATE FOR STOVES.

1,067,428.

Specification of Letters Patent.

Patented July 15, 1913.

Application filed January 19, 1910. Serial No. 538,877.

To all whom it may concern:

Be it known that we, WILLIAM E. HOLDER and RICHARD SAMPSON, both of the city of Montreal, in the Province of Quebec and 5 Dominion of Canada, have invented certain new and useful Improvements in Hot Plates for Stoves, of which the following is a full, clear, and exact description.

This invention relates to hot plates for 10 stoves and the main object of the invention is to provide a simple, inexpensive and efficient plate or stand which may be used over a single gas jet to heat either one or a plurality of cooking utensils at the same time.

15 A further object is to provide a device by means of which the heat from the gas flame is deflected toward the points where it is most needed to thus obtain the best results from a minimum amount of fuel.

20 The invention consists of a plate or stand having a peripheral depending flange upon which it rests, said plate being provided with two or more series of apertures through 25 which the heat rises to any utensil placed above same upon the stand. A thickened removable lid is fitted centrally into the plate and is convex or dome shaped on its under side to deflect the heat radially outward toward the apertures. Between the 30 sets of apertures the flange of the plate is curved inwardly to deflect the heat toward the apertures through which it is designed to pass.

35 In the drawings, Figure 1 is a plan view of the plate. Fig. 2 is an inverted plan view of the plate. Fig. 3 is a vertical sectional view on the line 5—5 of Fig. 1.

In the above defined figures 6 designates 40 a plurality of similar segments forming an approximately circular plate, the segments being secured together by means of flanges 7 and connecting bolts 8. The sections are so formed that when secured together the completed plate will have a plurality of substantially semicircular notches or depressions 45 9 in the outer edge thereof. The entire plate is supported on a peripheral depending flange 10 which follows the contour of the plate, as clearly shown in Fig. 2. Each 50 section of the plate is provided, between the notches 9, with a series of apertures 11 preferably arranged in radial rows with the apertures of one row staggered with respect to the apertures of adjacent rows, as shown 55 in the drawings. A centrally located circu-

lar lid 12 is provided which rests on a suitable supporting flange 13 to which it may be attached by bolts 14. It will be understood that when the plate is in operation the use of the bolts is optional as the lid 12 will 60 remain in position similarly to an ordinary stove lid. The top 15 of the lid is flat but the bottom 16 is convex or dome shaped for the purpose of deflecting the flame and heat toward the periphery of the plate. A suitable depression 17 containing a cross bar 18 may be provided in the center of the lid to coöperate with any ordinary stove lid lifter in the usual manner. The under surface of the plate is provided with a plurality of 70 concentric flanges or ridges 19 which project a short distance below the plate and serve to break the outrush of the flame and to direct it upwardly through the apertures 11. The plate and lid are both provided 75 with a plurality of small raised bosses 20 on the upper side thereof adapted to support a utensil placed on the plate a sufficient distance thereabove to allow the escape of flame and heat rising through the apertures 11. 80 It will be obvious that the form of the depressions 9 may be changed from semicircular to any other suitable shape without altering the purpose thereof or detracting from the efficiency of the device. 85

When in use the plate is placed over a gas jet or single burner of a gas or oil stove. The flame and heat rise into contact with the convex bottom of the lid and are deflected radially thereby to pass up through the 90 apertures 11 in the top of the plate. The flange surrounding the notches or depressions 9 also throws the heat toward the apertures 11 so that the heat is concentrated as it rises through the said apertures. 95

Having thus described our invention, what we claim is:—

1. A device of the class described comprising a plate having a plurality of sets of radial apertures arranged in concentric 100 rows, a plurality of concentric depending flanges on the lower surface of said plate positioned to intersect the apertures of adjacent rows, and a comparatively deep supporting flange for said plate adapted to prevent the escape of heat at the periphery thereof.

2. A device of the class described comprising a plate having a plurality of sets of radial apertures arranged in concentric 110

rows, a plurality of concentric depending flanges on the lower surface of said plate positioned to intersect the apertures of adjacent rows, a comparatively deep supporting flange for said plate adapted to prevent the escape of heat at the periphery thereof, said flange being inwardly curved between each set of apertures to equalize heat at the periphery and center of the plate, a central 5 removable lid for said plate, and a plurality 10

of bosses on the upper surface of the plate to support utensils thereabove.

In witness whereof we have hereunto set our hands in the presence of two witnesses.

WILLIAM E. HOLDER.
RICHARD SAMPSON.
